UNITED STATES PATENT OFFICE.

JOSEPH FAHYS, OF LOCUST VALLEY, NEW YORK, ASSIGNOR TO JOSEPH FAHYS & COMPANY, OF NEW YORK, N. Y., A CORPORATION OF NEW YORK.

DESIGN FOR A WATCHCASE BOW.

Application filed January 29, 1924. Serial No. 8,478. Term of patent 7 years.

To all whom it may concern:

Be it known that I, JOSEPH FAHYS, a citizen of the United States, residing at Locust Valley, in the county of Nassau and the State of New York, have invented a new, original, and ornamental Design for a Watchcase Bow, of which the following is a specification, reference being had to the accompanying drawing, forming part thereof.

In said drawing:

Figure 1 is a top plan view of a watch-

case bow embodying my new design, the bow being shown as applied to a conventional watch case indicated by dotted lines;

Figure 2 is a front plan view of the same;

Figure 3 is a side elevation; and

Figure 4 is a section taken along lines A—A of Figure 2.

I claim:

The ornamental design for a watchcase bow, as shown.

JOSEPH FAHYS.
